WINDING MACHINE.

Application filed July 3, 1926. Serial No. 120,469.

This invention relates to coil winding machines and comprises all the features of novelty herein disclosed, by way of example, as embodied in a machine for winding a strip of material into the form of a helix.

An object of the invention is to provide an improved machine for winding strip material into a continuous helical coil of small diameter and unlimited length. Another object is to provide an inexpensive and efficient machine of this character which is readily adaptable to the making of coils of different sizes, both as to internal and external diameters and as to wall thickness.

Still another object is to provide a machine which is adapted to handle tough material such as strip steel and make it into accurately formed hollow coils such as are used for roller bearings.

To these ends and to improve generally upon machines of this general character, the invention also consists in the various matters hereinafter described and claimed.

In the drawings, Figure 1 is a central longitudinal section of the machine, with some parts broken away.

Figure 2 is a side view, partly in section, of a coil being wound.

Figure 3 is a perspective view of the slide and saddle.

Figure 4 is a perspective view of a detail.

In general, the machine operates to feed a strip of material of substantially rectangular cross section endwise between two cones to form a coil which gradually decreases in size until the desired diameter is reached. The numeral 10 indicates a frame having bearings 12 and 14 for a rotatable shaft 16. An end thrust ball bearing 18 is interposed between a collar 20 on the shaft and the bearing 14 to take the thrust produced in one direction by the coiling operation. The end of the shaft is threaded at 22 to receive an internally threaded holder 24 carrying a cone member formed in large and small sections 26 and 28, respectively, the two sections forming a continuous external conical face and the smaller section 28 having a cylindrical extension 30. The smaller section is hardened and is detachably clamped to the larger section by a rod 32 extending through a central bore in the

larger section where its end is threaded to receive a clamping nut 34. As will appear, the smaller section can be easily replaced by another wherein the cylindrical extension has a different diameter. A shield 36 surrounds the cone member 26 and is detachably secured to the frame 10. The shield has an annular recess 38 to receive a removable strip-guiding plate 40 which surrounds the cone member and has a short conical face 42 intersected by a helical face 44. The entrance to the guide plate is a tangential slot 46 through which a strip S of windable material is fed.

In concentric relation to the inner cone member is an outer cone member 48 having an inner conical face and a cylindrical extension 50. The opposing cone faces are uniformly spaced throughout and so are the cylindrical extensions 30 and 50. The outer cone member is removably mounted in a recess of a rotatable holder 54 and outer cone sections of different interior diameter may be inserted in the recess as occasion arises. The conical face of the cone member 48 is substantially a continuation of the short conical face 42 of the strip-guiding plate 40 which is at the larger end of the cone and stationary, being keyed to the shield 36. This guiding plate is also replaceable by others of different interior diameter. Between a flange 56 on the holder and a slide or carrier 58 is interposed a ball thrust bearing 60 to take end thrust occasioned by the strong tendency of the cone members to separate axially during winding of a strip. The slide or carrier has a bore 62 acting as a journal for the rotatable holder 54 which has an opening 64 in line with the axis of the cones to allow the formed coil to feed out axially.

The slide 58 is adjustable in a direction parallel to the axis of the cones to regulate the space between the cones which space determines the wall thickness of the formed coil. The slide has lateral extensions provided with ways 68 that are slidable in guides 70 at the sides of a saddle 72 which is secured to the main frame. The slide also has a depending bored extension 74 which is guided on a shaft 78 journalled in a boss 80 of the saddle 72 and in bearings

84 and 86 of the main frame. The shaft 78 is driven by a gear 88 from a gear 90 on the driving shaft 16. The holder 54 is rotated by a ring gear 92 from a gear 94 on the end of shaft 78. These are wide gears which will effect driving connection in different positions of the slide and they are readily removable from the shaft and from an extension 96 of the holder so that gears having another teeth ratio can be substituted. The gear ratio is ordinarily such that the holder 54 and outer cone member will rotate about three times as fast as the inner cone member but this depends on the nature of the material, size of coil, etc. To move the slide, it is provided with a rack 98 fastened to its under side and operated by a pinion 100 on a short shaft 102 journalled in a lug 104 at one side of the saddle 72. The slide is removable endwise from the saddle to secure access to the cones and, when put back in adjusted position, is held by clamping plates 106, one of which is omitted in Figure 3 for clearness.

In operation, a single helical turn is made in a strip S of material by wrapping it around the base of the cone member 26 when the outer cone member 48 is displaced to the right in Figure 1. This turn can be readily made by a hand tool because there is little resistance to bending a coil of large diameter as compared to one of small diameter. This initial coil is then placed in the guiding plate 40 with the unwound part of the coil extending through the slot 46. The outer cone member is then adjusted to the proper distance from the inner one and the cone members are rotated, the outer one at a greater speed. This pulls the material endwise around the inner cone member and forms it into a coil which gradually decreases in diameter as indicated in Figure 2 until it passes out axially between the cylindrical sizing extensions 30 and 50. The guiding plate 40 initiates the formation of the coils after the first and the outer cone member stretches the material and irons it against the inner cone member. In some cases, the end of the strip of material can be fed through the tangential slot 46 without first forming an initial coil. Resistance to the winding of a steel strip directly into a helical coil of small diameter is very great compared to this winding of a large coil that is gradually decreased in size. The coils produced by this machine are more uniform and accurate and when cut up make better bearing rollers than those produced by the other method. The material can be wound either right handed or left handed by changing the direction of rotation of the cones and changing the guide plate 40.

Although the invention has been described by reference to a particular construction, it is not, in its broader aspects, necessarily lim-

ited to the form selected for mere illustrative purposes.

We claim:

1. In a machine of the character described, an inner cone member having an external 70 conical face, an outer cone member having an internal conical face surrounding the inner conical face, and means for causing a strip of material to be fed spirally between and in contact with said conical faces to 75 form a coil of gradually decreasing diameter; substantially as described.

2. In a machine of the character described, an inner cone member having an external conical face, an outer cone member having 80 an internal conical face surrounding and uniformly spaced from the inner conical face, and means for causing a relative movement of rotation between said cone members to form a strip of material into a coil; sub- 85 substantially as described.

3. In a machine of the character described, an inner cone member having an external conical face, an outer cone member having 90 an internal conical face surrounding and uniformly spaced from the inner conical face, means for rotating the inner cone member, and means for rotating the outer cone member at a faster speed than the inner cone member; substantially as described. 95

4. In a machine of the character described, an inner cone member having an external conical face, an outer cone member having an internal conical face surrounding and uniformly spaced from the inner conical face, a plate surrounding said inner cone member, said plate having a helical face and an intersecting conical face at the entrance to the space between said cone members, and means for rotating one of said cone members; substantially as described. 100 105

5. In a machine of the character described, an inner cone member having an external conical face, an outer cone member having 110 an internal conical face surrounding and uniformly spaced from the inner conical face, a plate surrounding said inner cone member, said plate having a helical face at the entrance to the space between said cone members, and means for rotating one of said 115 cone members; substantially as described.

6. In a machine of the character described, a cone member having an internal conical face, a member within said cone member for sizing the interior of a coil formed therein, 120 and means for rotating said cone member; substantially as described.

7. In a machine of the character described, a cone member having an internal conical face, a plate having a helical face at the 125 entrance to the larger end of said cone member, and means for rotating said cone member; substantially as described.

8. In a machine of the character described, a cone member having an internal conical 130

face, a plate having a helical face and an intersecting conical face at the entrance to the larger end of the cone member, and means for rotating said member; substantially as described.

9. In a machine of the character described, a cone member having an external conical face, and means surrounding the conical face for feeding a strip of material around and along said conical face to form a coil of small diameter; substantially as described.

10. In a machine of the character described, a cone member having an external conical face, a plate surrounding said conical face and having a helical face substantially normal to the axis of the cone member, and means surrounding the conical face for feeding a strip of material around and along said conical face to form a coil of small diameter; substantially as described.

11. In a machine of the character described, an inner cone member having an external conical face with a cylindrical extension, an outer cone member having an internal conical face with a cylindrical extension, and means for feeding a strip of material around and between said cone members to form a coil of small diameter; substantially as described.

12. In a machine of the character described, an inner cone member having an external conical face with a cylindrical extension, an outer cone member having an internal conical face with a cylindrical extension, a plate surrounding said inner cone member and having a guiding face at the larger end of said outer cone member, and means for causing a relative movement of rotation between said cone members to form a strip of material into a coil; substantially as described.

13. In a machine of the character described, an inner cone member having an external conical face, an outer cone member having an internal conical face, a holder for one of said cone members, and means for adjusting the holder parallel to the axis of said cone members; substantially as described.

14. In a machine of the character described, an inner cone member having an external conical face, an outer cone member having an internal conical face with a cylindrical extension, and a holder for said

outer cone member adapted to receive outer cone members of different sizes, and means for adjusting the holder parallel to the axis of the cone member; substantially as described.

15. In a machine of the character described, an inner cone member having an external conical face with a cylindrical extension, an outer cone member having an internal conical face, said inner cone member being in two sections and the larger section being adapted to receive smaller sections of different sizes, and means for causing a relative adjusting movement between said cone members in a direction parallel to their axes; substantially as described.

16. In a machine of the character described, an inner cone member having an external conical face, an outer cone member having an internal conical face, said inner cone member being formed in sections, the smaller section having a cylindrical extension, and means for detachably securing the smaller section to the larger section; substantially as described.

17. In a machine of the character described, an inner cone member having an external conical face with a cylindrical extension, an outer cone member having an internal conical face with a cylindrical extension, said inner cone member being formed in sections, the larger section being adapted to receive smaller sections of different sizes, a holder for said outer cone member, said holder being adapted to receive outer cone members of different sizes, and means for adjusting the holder parallel to the axis of the cone members; substantially as described.

18. In a machine of the character described, an inner cone member having an external conical face, an outer cone member having an internal conical face concentric with the conical face of the inner cone member, a holder for the outer cone member, said holder having a bore in alignment with the axis of the cone members, and means for rotating said holder; substantially as described.

In testimony whereof we hereunto affix our signatures.

JACOB C. HENNY.
